BALL COCK

George E. Geyer, Bloomfield, N. J.

Application March 8, 1938, Serial No. 194,698

3 Claims. (Cl. 137—104)

The present invention relates to new and useful improvements in ball cocks for flush tanks and has for one of its important objects to provide, in a manner as hereinafter set forth, a device of this character embodying a construction and arrangement which is such that quiet operation at all times may be had.

Another very important object of the invention is to provide a ball cock of the character described embodying a novel combination and arrangement of parts whereby siphoning of water and gases from the flush tank or bowl to the supply pipe will be positively prevented.

Other objects of the invention are to provide a ball cock of the character set forth which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view partially in vertical section and partially in side elevation, showing a ball cock constructed in accordance with the present invention.

Figure 2 is a top plan view of the invention, a portion thereof being broken away in section.

Figure 3 is a detail view in top plan of the valve lever, an end portion thereof being shown in section.

Figure 4 is a view in vertical section through the upper portion of the hush tube.

Figure 5 is a view in horizontal section through the upper portion of the hush tube and the clamp in which it is mounted.

Referring now to the drawings in detail, it will be seen that the embodiment of the invention which has been illustrated comprises a vertical pipe 1 of suitable metal which is adapted to be threadedly mounted on the upper end of the usual supply pipe in the flush tank (not shown). On the upper end of the pipe 1 is an integral valve casing 2. The casing 2 includes an upstanding externally threaded cylinder 3 in which a substantially cylindrical valve 4 is mounted for vertical movement. A face 5 of suitable material is secured in the lower end portion of the valve 4 for engagement with a seat 6 on the upper end of the pipe 1. Threadedly mounted for adjustment on the cylinder 3 is a cap 7. A

shank 8 extends upwardly from the valve 4 through an opening which is provided therefor in the cap 7. A gasket 9 is provided on the upper end of the valve 4 for preventing leakage through the opening in the cap 7 around the shank 8.

Formed integrally with the casing 2 is a split clamp which is designated generally by the reference numeral 10. The clamp 10 comprises complementary jaws 11 and 12 between which the upper end portion of a hush tube 13 is secured by a screw 14 in the projecting free end portions 15 of said jaws. The hush tube 13 is open at both ends. The upper end of the hush tube 13 is internally flanged in a manner to provide a splash shield or guard 16.

Rising from the clamp 10 is a pair of angular arms 17. A pin 18 extends between the free end portions of the arms 17 above the cap 7. Journalled on the pin 18 for swinging movement in a vertical plane is a lever 19 having a head 20 on one end thereof engaged with the upper end of the shank 8 for closing the valve 4 against the pressure of the water in the supply pipe. The other end portion of the lever 19 is provided with a threaded socket 21 for receiving the usual float rod 22.

In its upper end portion, the hush tube 13 has pressed therewith from its outer periphery a spiral channel 23 communicating at one end with the casing 2 for receiving water therefrom. The other end of the spiral channel 23 is open for communication with the hush tube 13. It will be observed that the portion of the hush tube 13 in which the spiral channel 23 is located is enclosed in the clamp 10. As best seen in Fig. 5 of the drawings, the spiral channel 23 is roughened, as at 24, in a manner to reduce the velocity of the water passing therethrough. The channel 23 may be of any desired pitch.

At a point in alignment with but spaced from the discharge end of the channel 23, the hush tube 13 has formed therein a port 25 (see Fig. 2). The reference numeral 26 designates a refill pipe to the bowl (not shown) which is tapped into the jaw 12 of the clamp 10 in communication with the port 25. A deflector 27 in the hush tube 13 directs a portion of the water from the channel 23 into the refill pipe 26 through the port 25. It will be noted that the port 25 communicates with the refill pipe 26 through a passage 28 in the jaw 12. The construction and arrangement is such that the volume of water flowing to the refill pipe 26 through the port 25 may be controlled by loosening the screw 14 in a manner to permit the hush tube 13 to be rotated in the

clamp 10, thus adjusting said port 25 relative to the passage 28. A teat 29 projects from the hush tube 13 and is operable in a recess 30 which is provided therefor in the clamp jaw 11 in a manner to limit the rotary adjustment of said hush tube in said clamp.

It is thought that the operation of the device will be readily apparent from a consideration of the foregoing. When the float (not shown) drops in the flush tank with the level of the water therein, the valve 4 is opened by the pressure of the water from the supply pipe and said water flows through the channel 23 and enters the hush tube 13. In passing through the spiral channels 23 the velocity of the water is reduced and said water is given a whirling motion as it enters the hush tube 13 and flows downwardly on the inner periphery thereof. A portion of the water from the spiral channel 23 is directed into the refill pipe 26 by the deflector 27. As hereinbefore stated, the port 25 may be controlled as desired by simply rotatably adjusting the hush tube 13 in the clamp 10. When the water level in the flush tank rises, the float operates the lever 19 in a manner to close the valve 4 against the pressure in the supply pipe. Through the medium of the adjustable cap 7 the stroke or travel of the valve 4 may be regulated as desired. As indicated in Fig. 1 of the drawings, the casing 2 and the clamp 10 are set in the horizontal plane of the upper end of the usual over-flow pipe (not shown) of the flush tank. The stop 29 engaged in the recess 30 of the clamp jaw 11 also facilitates proper positioning of the hush tube 13 in the clamp. From the foregoing it will be seen that it is virtually impossible for water or gases to be siphoned into the pipe 1 and the supply pipe from the flush tank or the toilet bowl.

It is believed that the many advantages of a ball cock constructed in accordance with the present invention will be readily understood and although a preferred embodiment of the device is as illustrated and described, it is to be understood that changes in the details of construction

and in the combination and arrangement of parts may be resorted to which will fall within the scope of the invention as claimed.

What is claimed is:

1. A ball cock comprising a casing for connection with a supply pipe for receiving water therefrom, a float operated valve in the casing for controlling the flow of water thereinto, a hush tube having a substantially spiral channel in its outer periphery communicating with the casing and with the interior of said hush tube, and a clamp on the casing for securing the hush tube thereto, said clamp constituting one of the walls of the channel. 5

2. A ball cock comprising a casing for connection with a water supply pipe for receiving water therefrom, a float operated valve in the casing for controlling the flow of water thereinto, a hush tube having a substantially spiral channel in its outer periphery having one end 15 portion communicating with the casing and its other end communicating with the interior of said hush tube, means for rotatably securing the hush tube to the casing, said hush tube further having a refill port therein adjacent said other end of the channel, and a baffle in the hush tube in opposed relation to said other end of the channel for directing a portion of the water therefrom into the refill port. 20

3. A ball cock comprising a casing including 30 a cylinder, a seat in said cylinder, a valve operable in said cylinder and engageable with the seat for controlling the flow of water into the casing, an adjustable cap threaded on the cylinder for controlling the travel of the valve, an 35 upstanding shank on the valve extending slidably through the cap, a gasket encircling the shank and engageable with the cap for preventing leakage through said cap around said shank, a clamp on the casing, a float operated lever 40 mounted on said clamp and engaged with the shank for closing the valve, and a hush tube mounted in the clamp for receiving water from the casing. 45
